STEGANOGRAPHIC TYPEWRITER

Fernand D'Auvraine, Brussels, Belgium

Application July 26, 1933, Serial No. 682,259
In Belgium August 5, 1932

9 Claims. (Cl. 197—4)

The present invention relates to a steganographic typewriter giving simultaneously the visible impression of the type selected by the depression of a key at the board, and a second type automatically brought forward according to an arrangement of the mechanism.

Such machine is provided with a key-board having types or characters of any writing whatever or of conventional symbols; it is constituted by a mechanism constructed according to the accompanying drawings, driven by a crank handle giving simultaneously the impression of a type-written symbol and of that automatically brought forward. The latter has a fictitious value, and will be used in deciphering to find the symbol for which it has been substituted.

The advancing of the fictitious symbol to the impression point is performed according to a disposition of a mechanism automatically moved by the crank.

After each depression of a key, the type selected to function is impressed by pulling the crank handle and simultaneously a second fictitious symbol is brought forward for impression. The succession of these fictitious symbols constitutes the steganographic or ciphered text.

For translating it into clear text, the machine is put again in the original starting position (detalled hereafter); the keys corresponding to the fictitious symbols obtained are lowered in the given succession and operation proceeds just as for producing the aforesaid steganogram.

In the drawings:

Fig. 1 is a side elevation partly in section;
Fig. 2 is a front view partly in section;
Fig. 3 is a plan view with parts broken away;
Figs. 4, 5 and 6 illustrate separately constructional details.

With reference to these drawings, the machine comprises a key-board, the keys 1003' of which have as index the type which they operate, said keys being protected by a cover ring 1001. The key levers 1005 extend longitudinally throughout the machine frame and are controlled by a spring 1004. Each key lever is pivoted to angle plates 1006, 1006', the free arms of which are in turn pivoted to a connection strip 1008. The angle plates 1006, 1006' are pivoted to transverse shafts 1009, whereas the spring 1004 is mounted upon a transverse rod 1029. The ends of the hair-pin-shaped spring extend down to a transverse T-iron 1010, and each connection strip 1008 has a projecting feather 1035 engaged within the return spring 1004.

The accurate position of the key levers is se-

cured by means of guiding and separating combs 1049, 1049', 1050, 1050', 1051, 1051' designate the pivots of a parallelogram allowing the key levers different movements referred to hereafter.

Underneath the key-board are pivoted a series 5 of spring-controlled detecting plates 1007 pivoted to the beaded portion 1052 of a transverse member 1017, which is pivoted about a transverse spindle 2030. Underneath the key-board is also arranged a square shaft 2016 slidably supporting 10 the combination drum 2001, the peripheral surface of which is provided with conical studs 2004 capable of moving the detecting plates 1007. The shifting of the combination drum is operated by a manipulator 2007 provided with a downwardly directed feather 2021 capable of engaging graduated recesses of a transverse scale member 2020 arranged at the front end of the machine.

At the left hand end of the shaft 2016 is keyed 20 a graduated disc 3001 intended for setting the start of rotation of the combination drum 2001. This disc is moved by a crank 3002 having a handle 3003. A pointer 3004 engaging the graduations of the disc 3001 is fixed to the machine 25 frame.

At the other end of the shaft 2016 is keyed a ratchet wheel 4001, capable of being rotated by a pawl 4008 pivoted to the crank arm 4005, which is driven by the coupling lever 4004 moved by 30 the main driving means of the typewriter.

4017 is a control lever capable of determining the number of teeth to be engaged by the spring-controlled pawl 4008 upon the ratchet wheel 4001. This lever 4017 runs along a toothed quadrant 35 4019 fixed to the machine frame.

The movements necessary for the central elements of the typewriter are transmitted from a crank handle through a friction clutch comprising male and female cones 5001 and 5002. A 40 toothed gear of large diameter 5011 transmits the movements to the central shaft 1604 and meshes with a pinion 1605 shown in dotted lines in Fig. 1 and in full lines in Fig. 2. The crank handle 1902, 1903, pivotable about a spindle 1901, is 45 connected to a transmission rod 5016, pivoted to a crank arm 1315 of the auxiliary shaft 1300, which rocks the rod 4004 by means of the crank arm 5017.

In the central portion of the typewriter above 50 the key levers 1005 is pivoted the clearing rocker 6001 provided with lateral bearings for coupling the clearing rings 6007 and 6008. In the bearings 6002 are pivots 6003 for the support members 6004 sustaining the clearing rings 6007 and 6008. 6005 55

is the pivot spindle for the rocker 6001. The clearing rings 6007 and 6008 act respectively upon the abutment plates 7003 and 8003 of the central control discs 7001 and 8001.

5 The bridge 6013 constituting a support for the rocker 6001 forms part with the bridge part 1201 referred to hereafter.

The clearing rocker is controlled by the arm 6025 keyed upon the shaft 6027, capable of being 10 rocked by arm 6026, the end of which is situated in the path of the reciprocating crank handle 1902—1903.

Upon the central shaft 1604 is keyed a disc 7001, provided at its periphery with a number of radial 15 slots, equal in number to that of the key levers 1005, said slots being intended for lodging abutment blades 7003. These abutment blades are pivoted to circular spindle 7002 and in front of the machine is pivoted, upon a spindle 1039, a 20 particular dog 7014, capable of moving by depression one of said abutment blades 7003. These abutment blades 7003 are frictionally held in their slots by washers 7018. The particular dog 7014 is linked by a rod 7025 to the universal bar 25 2101 rocking about a transverse shaft 2139.

Above the disc 7001 is arranged a freely rotatable disc 8001, also provided with a number of radial and vertical slots at its peripheral bead, said slots being in number equal to that of the 30 key levers 1005, and in which are also lodged a series of movable abutment blades 8003. This disc is also provided with a projecting feather 8001'. In this disc 8001, the movable abutment blades 8003 are pivoted to a circular spindle 8002 35 and this disc carries a type wheel 8004 having types corresponding to the key-board and intended for impression of the symbol pressed at the key-board.

The abutment blades 8003 are also frictionally 40 pressed by washers 8018. The upper end of the hub of said disc 8001 is provided with a cup-shaped member having an inclined rim 8050 intended to constitute a pulley groove with a similar element 1150.

45 9001 is a ring supporting the stop dogs 9003 pivoted on a circular spindle 9002. Each stop dog 9003 is connected by a rod 9020 to its corresponding key lever 1005.

At the upper end of the central shaft is keyed 50 a second type wheel carried by a disc 1101, supporting the plate 1103, which is provided with feathers 1102 arranged in circle about a central axis at equal distances the one from the other and in number equal to that of the keys of the 55 key-board. The type wheel 1104 is provided with the types intended for giving the impression of the fictitious symbols.

For varying the angular position of this type wheel 1104, a fork member 1105 is provided capable of lifting this type wheel and rocking about a ball pivot 1106, fixed by means of a set nut 1107 to a frame portion. The pins 1108 of the fork lever 1105 engage a groove of the hub 1103. Thus hub is also provided at its lower end with 65 a circular cup 1150 having an inclined rim fixed to the hub portion 1101 and cooperating with the cup element 8050 to constitute the V-shaped pulley groove at 90°, in which will be lodged a helical spring 1151, the ends of which are connected, so as to constitute an elastic ring securing the friction required for actually rotating the disc 8001.

The lower bridge member 1201 forming part of the central frame, constitutes a bearing for the 70 central shaft 1604 and also a support for the pivot

spindle 6005. 1202 is a bridge portion forming the other bearing for the central shaft 1604 and a support for the members 1105, 1703 and 1704 referred to hereafter.

To the auxiliary shaft 1300 is keyed a crank arm 1301 having a hub 1301'. To this crank arm 1301 is pivoted a finger 1302 intended for cocking the hammers 1303 and operating the impact of impression. The impression hammers 1303 are supported by and pivoted to spindle 1304 and have 10 extending arms 1305 acted upon by the finger 1302 pivoted to spindle 1307.

The ink ribbon spools 1402 and 1402' are supported by spindles 1401 and 1401'. The two ink ribbons 1430 are guided over rollers 1403, 1403'.

The paper tapes are moved by a driving roller pivoted to the spindle 1501, cooperating with a pressure roller 1502. The paper tape is guided over a roller 1502', the delivery bobbins 1504 of the tape 1530 being supported upon a shaft 1503 20 fitted with a supporting disc 1505.

1601 is a transmission shaft transmitting movement to the central shaft 1604, by means of the gears 1602, 1603, having helical teeth at 45°; said shaft 1601 has a pinion 1605 driven by the main gear 5011.

1701 and 1702 are spring-controlled abutment knobs intended for setting the type wheels at zero point. The knobs 1703 and 1704 when pushed towards the central shaft 1604 will bring the abutments 1701, 1702 in the path of the projections 1750, 1751 provided in the plane of the type wheels.

The universal bar 2101 rocking about the transverse shaft 2139 is driven by a rocking lever 2102, the upper end of which has a spring-controlled catch 2103 and the lower one a connection link 2104 pivoted to a projecting heel portion of the universal bar. The catch 2103 is pivotable about a spindle 2105 whereas the lever 2102 is pivoted about the spindle 2129.

The mechanism and working of the machine will be detailed hereafter under separate headings.

The key-board

Towards the front side is arranged a key-board 45 of an ordinary typewriter, the keys of which in undetermined number are distributed in vertical and horizontal rows at will.

For facilitating the present description, a machine should be considered as having 42 keys 50 staggered in two horizontal rows of ten keys and two horizontal rows of eleven keys, bearing each the symbol, the alphabetical character, the numeral or the punctuation they will put individually into action.

Each key 1003 makes part with a key lever 1005; the latter passes through the machine in horizontal direction from the front to the rear and forms a parallelogram movement by its uniting with the angle plates 1006 and 1006' and the coupling connection 1008. This whole pivots upon the main shafts 1009 of fixed position and is pivoted in the points 1050, 1050', 1051 and 1051'.

The horn-shaped springs each having two arms 1004 keep the key levers in their rest position (see 65 Fig. 2) by engagement of the stud 1035 fixed upon 1008, the stud being kept wedged between said arms. The T-section iron 1010 acts as stop point for 1004.

Each key 1003' may be depressed in the vertical 70 direction, over a distance required for an operation, or it may be lifted vertically, the spring 1004 having for a function to bring it back to the rest position when freed.

The springs 1004 are passed by their loop upon 75

the rod 1029, which passes through the machine from one side to the other and is fixed at each end within the frame.

Two separating combs 1049 and 1049' keep the 5 respective space between the levers.

The combining drum

Under the key-board is arranged the combining drum 2001.

10 This drum 2001 is formed as a cylinder provided with a hub bored with a square hole; it moves parallel to the axis of the square shaft 2016 which constitutes a support for same and which makes it revolve.

15 Upon the cylindrical periphery of the drum 2001, at the intersecting of a number of generatrices determined by the number of teeth of a toothed wheel 4001 and a number of circumferential lines corresponding with the axis of the 20 key levers 1005 which are overhead the drum 2001, threaded holes are drilled in the radial direction, intended to secure a lodging for conical studs 2004, which are placed therein at the ratio of one 25 per generatrix upon any circumferential line whatever.

Setting the start of rotation of the drum 2001

The start of rotation of the drum may be set at any point of its circumference by rotating the 30 crank 3002 and 3003 keyed upon the square shaft 2016, for bringing the required point of the graduated dial 3001 in front of the pointer 3004 which is fixed to the frame.

The quadrant setting

35 The rotation of the drum 2001 is operated by the pawl 4008, which acts upon the ratchet wheel 4001 fixed upon the square shaft 2016 and the number of teeth of which is selected at will for 40 determining the number of generatrices upon the combining drum 2001.

The crank arm 4005 is driven from the crank handle 1902 by means of the connection rods 5006 and 4004; it supports the pawl 4008 and moves it 45 in its circular reciprocating movement about the axis of the square shaft 2016.

The stroke of the crank 4005 is always of the same amplitude and may be determined for an angle comprising a number of teeth of the pawl 50 wheel 4001. The shutter lever 4017 is intended 50 for being inserted between the pawl 4008 and the ratchet wheel 4001 and according to the stopping point which it occupies along the toothed quadrant 4019, it will prevent the engagement of the 55 ratchet wheel 4001 by the pawl 4008 for one, two, three or X teeth.

The friction clutch

The clutch element 5002 fixed to the crank 60 handle 1902 frictionally moves the element 5001 fixed upon the large gear 5011. The whole is mounted upon the shaft 1901 which acts as rotation pivot for this clutch.

The clearing action

65 The elements necessary for this action are numbered 6001, 6002, 6003, 6004, 6005, 6007, 6008, 6013, 6025, 6026, 6027.

The clearing rocker is intended to bring the 70 movable abutments 7003 and 8003 to their rest position, as shown in Fig. 1. This rocking device is pivoted on shaft 6005 and rests upon a lever arm 6025. The bridge element 6001 is formed with two aprons in one plane, each supporting a 75 coupling bearing 6002.

Each bearing 6002 forms the seat for a pivot 6003 fixed in the arm 6004, both arms 6004 supporting a ring of I-section, the two flanges of which constitute the clearing rings 6007 and 6008 arranged coaxially with the central shaft 1604. 5

The rings 6007 and 6008 are lodged between the uprights of the bridge 1201, which act as vertical guides. In the inner free space of these rings 6007 and 6008 are mounted the discs 7001 and 8001, so that only the horizontal portions of the 10 abutments 7003 and 8003 are overhead the inner part of the flange of the rings 6007 and 6008.

The clearing rocker 6001 rocking upon its shaft 6005 only makes a reciprocating movement upwards with back motion downwards, according to 15 the operation of the lever 6025, with strokes the amplitude of which is determined by the shifting which is necessary for bringing the abutments 7003 and 8003 to their rest position, and the back movement downwards to put the rocker 6001 and 20 20 this complete machine part 6000 out of any reach of the rotary central portion which will be considered hereafter.

The rotary central portion

25 The rotary central portion of the machine is a whole of constructional elements to be detailed hereafter and rotating all around the axis of the central shaft 1604 upon which they are mounted.

Disc with movable abutments

30 The disc 7001 fixed by its hub upon the shaft 1604 supports at its periphery a bead of circular shape cut by 42 radial and vertical notches at equal distances the one from the other. In the 35 42 notches are lodged 42 movable abutments 7003 engaged upon the circular pivot spindle 7002. The abutments 7003 are made of sheet metal of about 1½ m/m thickness; they have the shape of an angle plate, the angle of which determines 40 the center of pivotment and is provided for this purpose with a hole through which passes the pivot 7002.

One of the arms of 7003 is vertical and is 45 turned towards the center of the disc 7001 with respect to its center of pivotment and projects from the bead at its upper portion; the horizontal arm of 7003 passing underneath the center of pivotment of 7002 projects out of the periphery of the disc 7001, so as to extend over 50 the flange of the clearing ring 6007. The part of the angle plate 7003 projecting horizontally out of the disc 7001 is bent at 90° for presenting more surface within the horizontal plane. Each blade 7003 is accompanied in its lodging by a 55 slotted pressure washer 7018 affording the required resiliency for maintaining an abutment 7003 by friction against the wall of the notch, so as to hold said abutment in any position to which it has been intentionally brought. 60

Second disc with movable abutments

This machine part comprises the following 65 elements: 8001, 8001', 8002, 8003, 8004, 8018, 8050.

The disc 8001 is integral with 8001', 8004, 1750 and 8050; it freely rotates upon the shaft 1604 and is provided at its periphery with a bead of circular section provided with a series of 42 radial and vertical notches at equal distances 70 the one from the other.

In the 42 notches of the bead are lodged 42 movable abutments 8003 accompanied by a slit pressure washer 8018 and engaged upon the circular pivot spindle 8002. 75

The movable abutments 8003 are made of sheet metal of about $1\frac{1}{2}$ m/m thickness; they are in the shape of an angle plate, the angle of which determines the center of pivotment and which 5 is provided with a hole for engagement of the pivot spindle 8002. One of the arms of 8003 is vertically directed and is turned outwardly from the center of the disc 8001 with respect to its pivotment center and projects from the bead of 10 8001 at its lower portion. The horizontal arm of 8003 starts from the center of pivotment, a portion of the arm bent at 90° being over the flange of the clearing ring 6008.

8001' is an abutment feather, formed at the 15 upper face of the disc 8001; it extends from the center of the shaft 1604 so as to come over the part of the dogs 9003 projecting inwardly of the stopping ring 9001. 8001' is intended for stopping the rotation of the disc 8001 when it meets 20 with a stopping dog 9003 which, by depression of a key at the board, is brought to position A and is situated in the plane of rotation of the feather 8001'.

The hub of the disc 8001 supports at the upper side a second disc 8004, forming part and concentric therewith, at the periphery of which are arranged on the plane of the rim, at equal distances from each other, 42 prominent types corresponding to the symbols of the key-board 25 of the machine. Each key causing by depression the meeting of 9003 with 8001' will stop, at the point of impression in front of the hammer 1303, the type of the wheel 8004 corresponding to the key acted upon. The hub of the disc 8001 supports at the end of its upper portion a circular dish 8050 with a rim inclined at 45° with respect to the bottom of the dish; it makes part with the hub and acts as driving pulley for rotation of the type wheels at the moment specified hereafter.

40 The ring and the stopping dogs

This part comprises the elements 9001, 8002, 9003 and 9020.

9001 is a ring to which are fixed the bridges 45 1201 and 1202; the central part of the ring leaves a free circular space for the reception of the rotary part of the machine mounted on the central shaft 1604 under the conditions required for the different movements.

50 Concentrically to the shaft 1604, the stopping ring 9001 has a vertical wall provided with a series of 42 radial and vertical slits which constitute guides for the stopping dogs 9003.

At a distance farther apart from the center 55 of 1604, a second series of 42 notches constitute a lodging for the stopping dogs 9003. This series of notches is arranged in a circular concentric bead forming part of the ring 9001. In the center of this bead passes the circular spindle 9002, 60 which constitutes a pivot for the stopping dogs 9003. The latter are distributed with their longitudinal axes along the radii starting from the center of 1604 and are spaced apart at equal distances from each other. The connection rods 65 9020 individually transmit to the stopping dogs 9003 the movements imparted by the different key levers 1005 from the position O towards A with back motion to O, or from O towards B with back motion to O, see Fig. 1, according to the 70 depression of a key 1003' at the board or the lifting by the universal bar 2101.

From each key lever 1005 starts only one connection rod 9020 towards one of the stopping dogs 9003 and each stopping dog 9003 is only moved

75 by one single key lever 1005 by means of the individual connection 9020.

Barrel with fictitious types

This part comprises the elements 1101, 1102, 5 1103, 1104, 1105, 1106, 1107, 1108 and 1109.

The disc 1101 with hub is keyed upon the shaft 1604 and rotates therewith. At a certain distance from this axis and according to a concentric circle, 42 holes are bored at equal distances apart 10 and at right angles to the plane of the circle and they are intended to be engaged by the pins 1102 wedged in the plate 1103 to connect the plate and the disc together. The symmetry of the pins with respect to the holes of the discs allows 15 an alteration in the relative positions of these two plates.

The plate 1103 forms part with the wheel 1104 the periphery of which is provided in the flat of the rim with 42 prominent types corresponding 20 to those of the key-board. These types are distributed in accordance with the succession of the stopping dogs 9003 around the ring 9001 and this succession is determined by the connection 25 of said dogs to the key levers 1005.

The lever 1105 is forked, the two arms being provided at their ends with pins 1108 which engage within the circumferential groove provided in the body of the hub of 1103. This fork rocking upon the ball pivot 1106, which is fixed after 30 adjustment in height by means of a nut 1107, has no other function than to lift the plate 1103 with the barrel 1104 for adjusting same with respect to the disc 1101.

1106 is a circular cup with flat bottom, the edges of which are inclined at 45° with respect to its bottom; it is fixed at the lower portion of the hub of disc 1101 with its edge turned upwards. The edge of these two cups 8050 and 1106 form a pulley rim with a right-angled groove 40 between them, in which is lodged a helical spring 1151 which, having its ends connected, completely embraces the periphery of the groove, and by its tension secures the friction required to make 45 8001 revolve under the rotation of 1103 in certain cases as will be seen hereafter.

The bridges of the central frame

This machine part comprises the elements 1201 and 1202.

1201 is an element having the shape of a suspension bridge, the horizontal apron of which is connected at the bottom by two vertical columns to a ring occupying the upper plane. This ring is carried by means of a circular flange in the ring of the stops 8001, is fixed thereto by screws and is concentric thereto.

The ring of this bridge 1201 leaves a free portion in its center for lodging the rotary portion 60 of the machine.

Between the pillars of the bridge 1201 are lodged the clearing rings 6007 and 6008 for which they act as guides.

The apron of this bridge constitutes the base 65 of the central portion, extends horizontally in the direction of the diameter of the ring of the bridge from the front to the rear, and is bored in its center vertically for the reception of the central shaft 1604 which takes seat in this bore.

Towards the front and at a distance determined by the radii of the gears 1602 and 1603, is provided a second bore at right angles to the foregoing for lodging the shaft 1601 which rotates therein about its axis.

The element 1202 is similar to that 1201. It is also fixed to the ring of the stops 9001 by engagement therewith and screws, and the latter constitutes the base of the bridge 1202, the apron 5 of which is at the upper portion and horizontal in the direction of a diametrical line and at right angles to the position of 1201.

At the rear of the apron and in the same plane is adjusted, at right angles thereto, another 10 apron supported by a third pillar which takes seat upon the ring and to which is suspended the lever 1105.

In the center of the apron 1202 is provided a bore for engagement of the shaft 1604.

15 In the vertical pillar of the bridge 1202 is provided an opening for the free movement of the lever 1105, the pivot 1106 of which is fixed in the apron.

In the left hand vertical pillar of the bridge 20 1202 (see Fig. 2) are mounted the knobs 1703 and 1704 to be examined hereafter.

Auxiliary movements and impression hammers

This section comprises the elements 1300, 25 1301, 1302, 1303, 1304, 1305 and 1307.

The whole of these elements constitutes a movement intended to actuate the hammers 1303 securing the impact for impression of the types.

30

Inking

This machine portion comprises the elements 1401, 1401', 1402, 1402', 1403, 1403' and 1430.

This mechanism cooperates to the regular shifting of the ink ribbon in order to keep the 35 inking clean.

Feeding of the impression paper

This section comprises the elements 1501, 1502, 40 1503, 1504, 1505 and 1530.

45 The visible impression of the types is simultaneously made upon two tapes of paper shifted according to the impact of the elements which secure the automatic progression after each record. The whole of the elements of which the numerals are cited secure this movement.

Transmission of the movement of the crank handle to the central shaft

This section comprises the elements: 1601, 50 1602, 1603, 1604, 1605.

The pinion 1605 is keyed upon the transmission shaft 1601, rotates therewith and is driven by the main gear 5011, which transmits the movements of the crank handle 1902.

55 The movements imparted to the pinion 1605 are transmitted by the gears 1602 and 1603 to the central shaft 1604.

1602 keyed upon 1601 is a toothed wheel with helical teeth which meshes with a similar gear 60 1603, the axes of the two gears being at right angles to each other.

This gear 1602 is keyed upon the central shaft 1604 and controls its rotation about their common axis.

65

Setting the machine in starting position

This section comprises the elements 1701, 1702, 1703, 1704, 1750 and 1751.

The stud 1751 is fixed to the wheel 1104 with 70 which it rotates about the axis of 1604, it passes in front of the spring-controlled abutment 1701, which is secured to the knob 1703, and remains clear of said stud 1751 during the working of the machine; said stud 1751 abuts this spring-controlled abutment 1701 when the latter is shifted

towards the center of the machine by the operator. This abutting makes the barrel 1104 stop in its revolution, so as to make it present always a determined point of the periphery of 1104, in front of one of the impression hammers 1303 5 and to cause the impression of a type which shall always be the same.

The stud 1750 fixed upon the wheel 8004 rotates with it about the center of the central shaft 1604, passes freely in front of the spring-controlled 10 abutment 1702 during the working of the machine; like the stud 1751, the stud 1750 only abuts with the spring-controlled abutment 1702 when the operator has shifted it towards the center of the machine by pressing the knob 1704 15 by means of a finger of his left hand. This abutting makes the wheel 1704 stop at a point determined upon its periphery which always brings the same type as the impression point in front of the hammers 1303. 20

Universal bar

This section comprises the elements 2101, 2102, 2103, 2104, 2105, 2129 and 2139.

The universal bar 2101 is in the shape of a blade 25 sustained by three arms fixed to the shaft 2139, which pivots about its axis in bearings provided in the frame of the machine and mounted at the rear of the detecting blades 1007 and slightly lower than the abutment heel of the latter, so 30 that they may come into position over said heel when they are brought backwards in position A under the action of the studs of the combination drum 2001.

35 Running in horizontal line under the key-board, the universal bar extends somewhat beyond the latter on either side, in order to secure its function upon all the key levers which it will have to operate according to the control given by the detectors 1007 obeying the conical studs 40 2004.

In its reciprocating movement, the crank 1902 makes the lever 2102 oscillate by means of 2103 which it strikes during its backward movement, 2102 oscillating upon 2129 pulls the connection 45 2104 which drives the universal bar 2101 and makes it oscillate about 2139.

This strike of the crank 1902 against 2103 lifts the universal bar 2101 and simultaneously the connection 7025 linked in the arm of 2101 and 50 50 actuated by the latter.

In its ascending movement, the universal bar 2101 lifts the connection 7025 which by making the special dog 7014 oscillate, rocks an abutment 7003 from the ring of movable abutment plates 55 7001; simultaneously, the bar 2101 strikes the abutment heel of the detector 1007 which extends over same, and rocks an abutment 8003 from the ring of movable abutments 8001 by means of the dog 9003 which it causes to oscillate from O to 60 B by lifting the lever 1005 and the connection 9020 under which the lifted detector 1007 is positioned.

The crank handle 1902 moves backwards until the moment when 2103 escapes from it; then the 65 universal bar falls back to its rest position with all its connected parts, as it may be seen in the drawings, Fig. 1, and the crank 1902 then continues its stroke towards the rear until its rest position, shown in the drawings, Fig. 1. 70

Working of the machine.—Preparation of the starting point

Before any transcription with the machine, it is indispensable to put the different elements in 75

a determined position in order to secure the reference points which in their whole constitute the key or starting point.

For this purpose:

- 5 (1) The starting of rotation of the combination drum 2001 is determined by rotating the handle 3002 for presenting the required graduation of the dial 3001 in front of the pointer 3004.
- 10 (2) After this, the position of the combination drum 2001 is determined with respect to the key levers 1005 by shifting it by means of the manipulator 2007 to introduce the pointing feather 2021 into the recess corresponding to the required graduation degree of the graduated scale.
- 15 (3) Afterwards the shutter lever 4017 is placed according to the number of teeth to be taken by the pawl 4008 upon the ratchet wheel 4001.
- (4) The lever arm 6026 is pulled forward to lift the clearing rings 6007 and 6008 and put all the 20 abutments 7003 and 8003 in their neutral positions.

Setting the start

To start the transcription of a clear text into a cabled text, after having set the machine to the different aforesaid positions, the type wheels 8004 and 1104 have to be brought in the starting position; for this, by means of the middle-finger of the left hand, the knob 1704 is pushed towards the center of the machine; it is kept so while, by means of the right hand, the crank handle 1902 is pulled forward; this causes the rotation of the shaft 1604, with the type wheels and the discs with movable abutments.

35 Under the friction of the spring 1151 in the groove formed by the cups 1150 and 8050, this rotation is transmitted to the disc 8004 which brings the stud 1750 against the spring-controlled abutment 1702 and stops its rotation there. At this moment, the spring 1150 slips and allows the type wheel 1104 and disc 7001 to revolve separately with the shaft 1604.

40 By means of the fore-finger of the left hand, the knob 1703 is then pushed inwardly to make the abutment 1701 project towards the center and against which the stud 1751 will strike. This will stop the rotation of the sections 1101, 1603, 7001, the large gear 5011 and the clutch cone 5001, which the handle 1902 had brought in rotation by friction.

45 50 Continuing its forward stroke, the handle 1902, by means of the connected parts and of the mechanism, throws in the hammers 1303 which impress the types which the wheels 8004 and 1104 have kept in front of the impression point after stopping. Arriving at the end of its forward stroke, the handle 1902 causes the lifting of the section 6001 by abutting the arm 6026, which oscillates about 6027 the arm 6025 engaging 6001.

55 60 During its forward stroke, the handle 1902 drives also the pawl 4008 which causes the drum 2001 to rotate about its axis over a distance determined by the number of teeth selected by the shutter lever 4017.

65 At this moment, the drum 2001 presents one of its conical studs 2004 in front of one of the detectors 1007 (see Figs. 1 and 3), which will be put separately backwards. This detector 1007 in the drawings is shown under the axial line of the key lever 1005 bearing the type X.

70 75 Moving backwards, the handle 1902 first frees the element 6001 which lowers to its neutral position, then strikes the movable catch 2103 to actuate the universal bar 2101, which will lift the detector 1007 and the key lever 1005 type X.

By means of the connection 9020, the key lever 1005 type X will oscillate the corresponding stop dog 9003 from O to B, which in turn will press upon the part bent at 90° of the movable abutment 8003 held at this moment in front of it.

Said abutment 8003 by turning about the axis of the circular pivot 8002 will incline its vertical arm and move its end towards the center. It is kept in this position and it can be designated as brought in function or cocked.

10 Simultaneously with the key lever 1005 the universal bar 2101 makes the special dog 7014 oscillate by lifting the connection 7025 and puts also in function the movable abutment 7003 which is in front of the dog 7014.

15 At the moment when the handle 1902 allows the escape of the movable catch 2103, while continuing its stroke towards the rear, the freed universal bar 2101 drops downwards and allows the dogs 7014 and 9003 acted upon to return in their neutral position such as they may be seen in the drawings, Fig. 1.

20 25 When the handle 1902 arrives at the end of its rear stroke, the operator frees the knobs 1703 and 1704 which he has kept pushed inwards during the forward and rear strokes of the handle 1902.

30 At this moment, a movable abutment 8003 is cocked upon the disc 8001 and a movable abutment 7003 is cocked upon the disc 7001; the latter are kept cocked by the pressure exerted upon the walls of their lodging by the slotted washers 7018 and 8018 which are associated therewith in their notches. This represents the machine at the moment for starting the transcription of the clear text in cabled.

Working of the machine

35 40 For this purpose, the first type to be written is depressed at the key-board with one finger of the left hand. This depression lowers the key lever 1005 which pulls upon its individual connection 9020 and upon the stop dog 9003 corresponding thereto; the latter by oscillating from O to A upon the pivot 9002 brings its free part inside the ring 9001 within the plane of rotation of 8001.

45 50 At this moment the crank handle 1902 is pulled forward; the latter makes the central shaft 1604 rotate which by revolving drives the discs 7001 and 1101 and also disc 8001 by friction of the spring 1151. Said disc 8001 will rotate until the moment when the feather 8001' will strike the dog 8003 of the key which the operator keeps within the plane of revolution.

55 60 The discs 7001 and 1101 will continue their revolution until the abutment 7003 which has been cocked upon the disc 7001 by setting the start of the foregoing operation, will strike the abutment 8003 also cocked upon the disc 8001. These two abutments will strike each other, because the vertical arm of each is in the path of revolution of the other owing to the inclination which is imparted to them by putting them into operative position.

65 70 The whole central rotary portion of the machine stops here its revolution and at this moment the female cone 5002 of the friction clutch slips upon 5001 and allows the handle 1902 to continue its forward stroke for causing the operation of the hammers 1303 and securing the impression of the types presented by the wheels 8004 and 1104 at the spot of impression.

75 After having performed the impression of the types, the handle 1902 strikes the lever 6026, while continuing its forward stroke and provokes the ascensional movement of the clearing section 75

6000, which puts the cocked abutments 7003 and 8003 in their neutral position just at the moment when the handle 1902 arrives at the end of its forward stroke, just like at setting at starting 5 position; at the backward movement, the handle 1902 first frees the lever 6026, which allows the clearing elements 6001/6008 to drop down to their neutral position. Then it engages the catch 2103, which controls the universal bar 2101 for the 10 cocking of an abutment 7003 and for the cocking of an abutment 8003 by one of the stop dogs 9003 put in action by another conical stud 2004 of the drum 2001.

After cocking the movable abutments 7003 and 15 8003 the handle 1902 is brought to its neutral position and the operator frees the key which he has kept depressed and which represents the first type of the text to be written.

When the operator has brought the handle 20 1902 to its neutral point, he may immediately depress at the key-board the second type of the clear text to be written, then pull the handle 1902 as herebefore, bring it back to its starting point and then free the key at the board at the last moment. For each type he will operate in the same 25 manner up to the end of the text.

Under these conditions, the types presented for 30 impression by the wheel 8004 will correspond to those selected at the keyboard and a fictitious text will be impressed by the wheel 1104.

Example

For the following words depressed at the key- 35 board; CRYPTOGRAPHE SCYTAL presented by 8004, the wheel 1104 will perhaps present: AKRITZAMZIZ KKRAMI; this depends upon the different settings and upon the relation selected between the key-board and the distribution 40 of the stop dogs 9003 in the ring of stops 9001.

I claim:

1. A steganographic typewriting machine of the hammer-impression type, comprising a frame, 45 a key-board, key levers capable of being shifted downwards and upwards, a central vertical shaft, two type wheels on said shaft and adapted to be rotated thereby, one of the type wheels being capable of variable angular movement with respect to the other for simultaneously producing a visible impression in clear writing and a cabled impression, two independent discs mounted on said central shaft and rotatable about the axis thereof, series of movable abutments on said discs, 50 said abutments allowing the free rotation of each disc, but capable of being moved to be in the path of rotation of each other, so as to cause the rotation of one disc by the other, each disc being integral with one type wheel, an oscillating universal bar, a dog controlled by said universal bar to move an abutment of one disc, a combination 55 drum, means moved by said drum so as to become engaged by the universal bar for the purpose of shifting a key lever upwards, a dog controlled by said upwardly moving key lever to move an abutment of the second disc, a stop dog controlled by the key lever depressed at the key-board, a projection on the disc associated with the type wheel for clear impression, and driving 60 means for imparting the various movements to the elements.

2. In a steganographic typewriter of the type set forth, a combination drum formed with a cylindrical body shiftable along a square shaft and rotated thereby, said shaft being arranged

transversely underneath the key-board, conical studs arranged upon the peripheral surface of the drum, oscillating detecting plates operated by said studs, and an oscillating universal bar engaging said detecting plates.

3. In a steganographic typewriter of the type set forth, a combination drum formed with a cylindrical body shiftable along a square shaft and rotated thereby, said shaft being arranged transversely underneath the key-board, conical 10 studs arranged upon the peripheral surface of the drum, said studs being arranged at the intersection of a number of equidistant generatrices and a series of peripheral circular lines corresponding to the axes of a number of adjacent key 15 levers, a ratchet wheel at the end of the square shaft, said ratchet wheel having a number of teeth corresponding to the number of generatrices on the drum, a pawl for rotating the ratchet wheel, oscillating detecting plates operated by 20 said studs and an oscillating universal bar engaging said detecting plates.

4. In a steganographic typewriter of the type set forth, a combination drum formed with a cylindrical body shiftable along a square shaft 25 and rotated thereby, said shaft being arranged transversely underneath the key-board, conical studs arranged upon the peripheral surface of the drum, said studs being arranged at the intersection of a number of equidistant genera- 30 trices and a series of peripheral circular lines corresponding to the axes of a number of adjacent key levers, a ratchet wheel at the end of the square shaft, said ratchet wheel having a number of teeth corresponding to the number of genera- 35 trices on the drum, a pawl for rotating the ratchet wheel, oscillating detecting plates operated by said studs, an oscillating universal bar engaging said detecting plates, and means for setting the starting point of rotation for the 40 square shaft.

5. In a steganographic typewriter of the type set forth, a combination drum formed with a cylindrical body shiftable along a square shaft and rotated thereby, said shaft being arranged 45 transversely underneath the key-board, conical studs arranged upon the peripheral surface of the drum, said studs being arranged at the intersection of a number of equidistant generatrices and a series of peripheral circular lines corre- 50 sponding to the axes of a number of adjacent key levers, a ratchet wheel at the end of the square shaft, said ratchet wheel having a number of teeth corresponding to the number of genera- 55 trices on the drum, a pawl for rotating the ratchet wheel, oscillating detecting plates operated by said studs, an oscillating universal bar engaging said detecting plates, means for setting the starting point of rotation for the square shaft, and means for putting a number of teeth 60 of the ratchet wheel out of operation.

6. In a steganographic typewriter of the type described, a frame, a central shaft, a pair of type wheels on said shaft, a pair of discs on said shaft associated with said type wheels and arranged to rotate the type wheels, movable abutments on said discs for controlling such rotations, and a clearing rocker pivoted within the frame for moving said abutments in their non-operative position, said rocker comprising a ring of 65 I-section, coaxial with said shaft and the flanges of which act on the abutments, guide ways for the ring, a rocking plate and a lever acting on said plate.

7. In a steganographic typewriter of the type described, a central shaft, a pair of type wheels, a pair of discs controlling the angular position of the type wheels, said discs having a peripheral bead, equidistant radial and vertical slots in said bead, rocking abutments lodged in said slots, said abutments being in the shape of angular plates pivoted at their apex to a common circular shaft, and washers frictionally holding said abutments 10 in their different positions.

8. In a steganographic typewriter of the type described, a frame, a central shaft, a pair of type wheels on said shaft, a projection on said type wheels, a pair of spring-controlled abutment

knobs mounted in the frame and capable of each engaging a projection for the purpose of setting the type wheels in a starting position.

9. In a steganographic typewriter of the type described, a frame, a transverse universal bar 5 rocking about a transverse shaft and having a projecting heel portion, a lever pivoted to the frame, a pivoted strip connecting the projecting heel of the universal bar to one end of said lever, and a reciprocating crank handle, the free end of said lever being in the path of said reciprocating handle.

FERNAND D'AUVRAIN.
